MESNE ASSIGNMENTS, TO THE UNION SWITCH & SIGNAL COMPANY, OF SWISSVALE,
PENNSYLVANIA, A CORPORATION OF PENNSYLVANIA

CONTROL OF DOORS OR GATES FOR MINING AND OTHER PURPOSES

Application filed October 10, 1927, Serial No. 225,106, and in Great Britain March 8, 1927.

Our invention relates to the control of doors or gates for mining and other purposes in which two or more doors or gates are required to be manually controlled from a distant point, and particularly although not exclusively to the control of the entrance and exit doors of air locks in collieries. In such cases the point of control is usually situated adjacent to one or other of the doors or gates and while the operator is in a position to observe that the proper number of tubs or trucks have passed through the door or gate near to him, he cannot, in most cases, be assured from observation that the tubs or trucks are clear of the more remote door or doors before effecting the closure of these.

The invention accordingly has for its object to provide arrangements whereby the closure of a door or gate distant from the point of control is automatically prevented unless the passage of tubs or trucks through the door or gate has been completed and the latter is consequently free to be closed without risk or damage.

According to the invention this result is attained by providing arrangements for superseding the action of the control valve at the point of control as regards the closing action of each of the doors or gates remote from the point of control in such a manner as to permit this closing action only under conditions in which the door or gate is free to be closed.

The invention is illustrated by way of example in the accompanying drawing, the single figure of which is a diagrammatic view illustrating the invention as applied to the entrance and exit doors of a colliery air lock, these doors being arranged to be opened and closed by fluid under pressure.

Referring now to the drawing, the entrance door of the air lock is indicated at 1, and the exit door at 2, the point of control being on the outer side of the door 1 and adjacent thereto. The door 1 is provided with operating mechanism comprising a cylinder 3, to which fluid under pressure is supplied to effect the opening of the door, the release of fluid under pressure from the cylinder 3 permitting the door to close under the action of

gravity. The door 2 is provided with a similar operating cylinder 4, a control valve 5 being arranged on the outer side of the door 1 at the point of control. The door 1 is provided with an interlocking device 6 adapted when the door 1 is closed to maintain an interlocking valve 7 in the position shown, the door 2 being provided with a similar device 8 adapted to operate an interlocking valve 9. On the outer side of the exit door 2 and adjacent thereto is an axle-counter 10 of any suitable type adapted in the position shown to maintain a restraining valve 11 in such a position as to establish communication between a pipe 12 and an exhaust outlet 13. When, however, a predetermined number of tubs or trucks have passed over the axle-counter 10 the latter is arranged to reverse the restraining valve 11 so as to establish communication between a supply pipe 14 leading to a source of fluid under pressure and the pipe 12.

The control valve 5 is adapted to be set into any one of three operative positions the valve being of any suitable construction adapted when the handle 15 of the valve is in its middle position, as shown, to establish communication between pipes 16 and 17 and the atmosphere. When, however, the handle 15 of the valve 5 is moved towards the right, fluid pressure is arranged to be supplied from a supply pipe 18 to the pipe 17, the movement of the valve handle towards the left similarly establishing communication between the pipe 18 and the pipe 16. The pipe 16, as shown, leads to the interlocking valve 9 for the door 2, communication being established through this valve when the door 2 is closed between the pipe 16 and a pipe 19 leading to the operating cylinder 3 of the door 1. When, however, the door 2 is opened, the interlocking valve 9 is reversed, and communication is established between the pipe 19 and an exhaust outlet 20.

The pipe 17 leads to a check valve 21 adapted alternatively to establish communication between the pipe 17 and a pipe 22 leading to the interlocking valve 7 of the door 1, or between this latter pipe and the pipe 12 leading to the restraining valve 11. The interlocking valve 7 when the door 1 is closed

establishes communication between the pipe 22 and a pipe 23 leading to the operating cylinder 4 of the door 2, while when the door 1 is opened communication is established between the pipe 23 and an exhaust outlet 24.

5 The operation of the arrangements above described is as follows:

With the control valve handle 15 in the position shown in the drawing, the doors 1 10 and 2 are both closed, the operating cylinder 3 being open to atmosphere through the pipe 19, the interlocking valve 9, pipe 16 and the control valve 5, the operating cylinder 4 being similarly open to atmosphere through 15 the pipe 23, the check valve 21, pipe 12 and the restraining valve 11.

When it is desired to admit a number of 20 tubs or trucks into the air lock the door 1 is opened by moving the handle 15 of the control valve towards the left, thereby supplying fluid under pressure from the pipe 18 through the pipe 16, the interlocking valve 9 (providing the door 2 is fully closed) and the pipe 19. The opening of the door 1 will 25 evidently reverse the position of the interlocking valve 7 so that so long as this door is open the operating cylinder 4 of the door 2 is in communication with the atmosphere through the pipe 23 and the exhaust outlet 30 24 of the interlocking valve 7. The door 2 consequently cannot be opened until the door 1 has been fully reclosed. As soon as 35 the tubs or trucks have passed into the air lock the operator will return the handle 15 of the control valve 5 to its middle position, thereby effecting the reclosing of the door 1 by venting the fluid under pressure in the operating cylinder 3 through the pipes 19 and 16 to the atmosphere at the control valve 5. 40 The door 1 having been fully reclosed, the door 2 may be opened by moving the control valve handle 15 to its right-hand position in which fluid under pressure is supplied from the pipe 18 to the pipe 17, reversing 45 the position of the check valve 21, the fluid thus passing through the pipe 22, the interlocking valve 7 and the pipe 23 to the operating cylinder 4.

The door 2 being opened, the tubs or trucks 50 in the air lock pass out through the door 2 over the axle-counter 10, and the action of the first tub or truck in thus passing over the axle-counter reverses the position of the restraining valve 11, with the result that 55 communication is established between the pipe 14 and the pipe 12, fluid under pressure being thus supplied through the pipe 12, the check valve 21, the pipe 22, the interlocking valve 7 and pipe 23 to the operating cylinder 4 of the door 2. It will be observed that 60 the supply of fluid under pressure to the cylinder 4 as above described is independent of the supply of fluid under pressure to this cylinder through the pipe 17 leading to the 65 control valve 5, so that even if the handle 15

is returned by the operator to its middle position, thereby cutting off the supply of fluid under pressure to the pipe 17, the operating cylinder 4 will still be supplied with fluid under pressure by way of the pipes 12, 22 70 and 23. Regardless of any action by the operator, therefore, the door 2 will be maintained open until a predetermined number of tubs or trucks have passed over the axle-counter 10 corresponding to the number originally contained in the air lock, and when this predetermined number of vehicles has passed the restraining valve 11 will be restored to the position shown with the result that the pipe 12 is in communication with 80 the exhaust outlet 13. In these circumstances, that is to say after the tubs or trucks contained in the air lock have passed over the axle-counter 10 and are fully clear of the door 2, the operator by moving the control valve handle 15 to the position shown can effect the release of fluid under pressure from the cylinder 4 by way of pipes 23, 22 and 17. Had the operator restored the handle 15 to its middle position before the predetermined number of tubs or trucks had passed the counter 10, the operation of this counter by the last of such tubs or trucks would automatically cause door 2 to close due to the exhaust of air from cylinder 4 90 through pipe 23, valve 7, pipe 22, valve 21, pipe 12, valve 11, and pipe 13.

It will be observed that the action of the control valve 5 to effect the release of fluid under pressure from the operating cylinder 4 to permit the door 2 to close is thus restrained or prevented until the predetermined number of tubs or trucks have passed over the axle-counter 10 and are clear of the door.

The invention is evidently not limited to the particular arrangements above described and illustrated which may be varied in many respects without exceeding the scope of the invention.

Having now particularly described and ascertained the nature of our said invention and in what manner the same is to be performed, we declare that what we claim is—

1. In combination, a mine door, an axle counter operated by vehicles passing through the door, a manually operable device, and means for controlling said door jointly by said device and by said axle counter.

2. In combination, a mine door, an axle counter operated by vehicles passing through the door, manually operable means for controlling said door, and means controlled by said axle counter for preventing said door from closing while vehicles are passing through the door.

3. In combination, a mine door biased by gravity to the closed position, a fluid pressure motor for opening said door, manually operable means for supplying fluid pressure to

said motor, an axle counter operated by vehicles passing through said door, and auxiliary means controlled by said axle counter for supplying fluid pressure to said motor.

5 4. In combination, a mine door biased by gravity to the closed position, a fluid pressure motor for opening said door, manually operable means for supplying fluid pressure to said motor, an axle counter operated by vehicles passing through said door, and means controlled by said axle counter for supplying fluid pressure to said motor while vehicles are passing through said door if the supply from said manually operable means 10 ceases.

15 5. In combination, a mine door biased by gravity to the closed position, a fluid pressure motor for opening said door, a pipe 22 normally connected with said motor, a pipe 20 17, manually operable means for connecting pipe 17 with atmosphere or with a source of fluid pressure, a pipe 12 normally connected with atmosphere, means operated by vehicles passing through said door for connecting pipe 12 with a source of fluid pressure, and a check valve associated with pipes 22, 25 17, and 12 for connecting pipe 22 with pipe 17 when pipe 17 is supplied with fluid pressure but for connecting pipe 22 with pipe 12 when pipe 17 is connected with atmosphere and pipe 12 is supplied with fluid pressure.

30 6. In combination, a mine door biased by gravity to the closed position, a fluid pressure motor for opening said door, a pipe 22 35 normally connected with said motor, a pipe 17, manually operable means for connecting pipe 17 with atmosphere or with a source of fluid pressure, a pipe 12 normally connected with atmosphere, an axle counter operated by vehicles passing through said door, means controlled by said axle counter for disconnecting pipe 12 from atmosphere and connecting it with a source of fluid pressure while a predetermined number of vehicles are passing 40 through the door, and a check valve associated with pipes 22, 17, and 12 for connecting pipe 22 with pipe 17 when pipe 17 is supplied with fluid pressure but for connecting pipe 22 with pipe 12 when pipe 17 is connected with atmosphere and pipe 12 is supplied with fluid pressure.

45 7. In combination, a mine door biased by gravity to the closed position, a fluid pressure motor for opening said door, manually operable means for supplying fluid pressure to said motor, an axle counter operated by vehicles passing through said door, a valve having a normal position wherein it does not influence said motor, means operating when said valve is in its reversed position for supplying fluid pressure to said motor independently of said manually operable means, and means operated by said counter for reversing said valve when a vehicle passes through 50 said door and restoring it to normal position

after the passage of a predetermined number of vehicles.

8. A mine air lock comprising two doors each biased by gravity to the closed position, a fluid pressure motor for opening each door, manually operable means for supplying fluid pressure to one or the other of said motors, and means for preventing the supply of fluid pressure to the motor for one door unless the other door is closed.

75 9. A mine air lock comprising two doors each biased by gravity to the closed position, a motor for opening each door, manually operable means for supplying operating energy to one or the other of said motors, and means for preventing the supply of operating energy to the motor for one door unless the other door is closed.

80 10. A mine air lock comprising two doors each biased by gravity to the closed position, a fluid pressure motor for opening each door, a valve associated with each door and having a normal position when the door is closed but a reverse position when the door is not closed, a fluid pressure supply pipe for each door, means controlled by the valve for each door for connecting the motor for the other door with its associated supply pipe or with atmosphere according as the valve is in its normal or its reverse position, and manually operable means for supplying fluid pressure to one or the other of said supply pipes.

85 11. A mine air lock comprising an entrance door and an exit door, manually operable means for controlling said doors, means for preventing either door from opening unless the other door is closed, and means operating when the second door has been opened and a train of vehicles has started to pass therethrough to prevent such door from closing until a predetermined number of vehicles have passed.

In testimony whereof we affix our signatures.
